UNITED STATES PATENT OFFICE.

DONALD S. BARROWS, OF ROCHESTER, NEW YORK.

STRIKING CASTING.

Application filed February 12, 1927. Serial No. 167,700.

This invention relates to combined castings used in connection with draft gear for railway cars and, more particularly, to such castings adapted to function as striking castings and receive replaceable carrier blocks.

The principal object of my invention, generally considered, is the provision of a combined casting which is formed with portions serving, respectively, as a striking casting or coupler stop member and a sill tie member or coupler carrier iron, said latter member being bowed downwardly at its intermediate portion to provide a greater opening for receiving parts of the draft rigging and provided with end portions adapted to support and retain a removable carrier block.

An object of my invention is the provision of a combined casting formed with striking and carrier iron portions, said carrier iron portion being bowed downwardly between the ends thereof to provide greater clearance for the butt of an associated coupler which may be of the swivel butt type, thereby having a butt of greater dimensions than the shank thereof.

Another object of my invention is the provision of a combined casting adapted for connection with the underframe of a car and formed with coupler striking and carrier iron portions, said carrier iron portion being adapted to support a carrier block at the ends thereof and provided with an intermediate portion normally spaced from said carrier block whereby, upon removal of said block, a relatively large opening is provided.

A further object of my invention is the provision of a combined casting adapted for connection with the center sills of a car and formed with a coupler striking portion and sill tie member, said members being connected at the corresponding ends by substantially vertical webs which are, in turn, connected with the adjacent ends of the sills, one of said webs being apertured above said carrier iron portion and a carrier block or coupler supporting member inserted through said aperture and supported at its opposite ends on said sill tie member, undesired removal of said block being prevented by a retaining pin extending across said aperture.

A still further object of my invention is the provision of a combined casting provided with a coupler stop or striking portion and a sill tie or carry iron portion, the corre-

sponding ends of said portions being connected by substantially upright web portions, one of said web portions being formed to provide a pocket above said carry iron and the other of said web portions being correspondingly apertured, a carrier block inserted through said aperture and moved until the corresponding end is received in said pocket with the other end retained in said aperture, and retaining means extending across said aperture adjacent the corresponding end of said block for preventing undesired removal thereof.

Other objects and advantages of the invention relating to the particular arrangement and combination of the various parts will become apparent as the description proceeds.

Referring to the drawings illustrating my invention, the scope whereof is defined by the appended claims.

Figure 1 is a longitudinal sectional view of a combined casting embodying my invention, said casting being shown connected to center sills and an associated coupler being diagrammatically illustrated in normal position.

Figure 2 is a plan of the embodiment illustrated in Figure 1 with the coupler omitted, the view being partly in section on the line 2-2 of Figure 1 looking in the direction of the arrows.

Figure 3 is a front elevational view of the combined casting embodying my invention, said casting being shown partly in section on the line 3-3 of Figure 2 looking in the direction of the arrows.

Figures 4 and 5 are views corresponding, respectively, to Figures 1 and 3 but showing another embodiment of my invention.

Figure 6 is a fragmentary horizontal sectional view on the line 6-6 of Figure 5 looking in the direction of the arrows.

Figure 7 is a fragmentary elevational view looking from the right at the embodiment illustrated in Figure 5.

Referring to the drawings in detail, like parts being designated by like reference characters, and first considering the embodiment of my invention illustrated in Figures 1, 2 and 3, there is shown a combined casting 1 formed with a coupler striking or stop portion 2, a coupler carrier portion or sill tie member 3 and substantially upright connecting web portions 4 formed with rearwardly extending connecting ears or flange

portions 5 which, in the embodiment shown, are connected to associated center sills 6 by means of a plurality of rivets 7. In the embodiment shown, the sills are slotted to 5 the ends as indicated at 8 and the rearwardly extending portions 5 of the combined casting 1 are adapted to function as the forward portions of cheek plates, that is, they are adapted to reinforce the slotted 10 portions of the sills which receive a usual form of draft key (not shown) as will be understood.

The striking casting portion 2 of the combined casting 1 is preferably formed 15 with an upright web portion 9 adapted for engagement with the horn of the coupler 10, illustrated diagrammatically by dot and dash lines, upon sufficient rearward movement thereof, and a lower inwardly extending 20 web portion 11 overlying the shank of said coupler. Extending from the upper edge of the web portion 9, continued rearwardly and adapted to extend beneath the sill cover plate (not shown) and end sill (not 25 shown) is a shelf or web portion 12. The rearward portion of said shelf may be downwardly offset, if desired, as indicated at 13. For bracing the web portions 9, 11, 12 and 13 together, longitudinally extending web 30 portions 14 are preferably provided, which gradually taper from the rear edge of the web 11 and finally merge into the web 13. Said web 12, at the front of the center sills 6, preferably extends transversely beyond 35 said center sills and the overhanging portions 15 are preferably braced with respect to the web portions 4 by means of transversely extending substantially vertical web or flange portions 16 which preferably extend substantially the full height of the combined casting. These webs or flanges 16 are, in turn, braced to the web portions 4 by web or gusset portions 17 and the corresponding portions of the web 12.

45 Between the center sills and rearwardly of the ends thereof, that portion 13 of the web 12 is formed narrower than the remainder of said web so as to extend between the sills 6 without intersecting the same and 50 is preferably positioned so that the top is substantially flush with the tops of the sills. This construction makes it possible to rigidly connect the end sills and center sills while providing for the secure connection between 55 the combined casting 1 and the cover plate and center sills. The narrower portion 13 is preferably extended for a substantial distance to underlie the end sill and, as will be apparent from a consideration of Figure 60 1 particularly, it preferably extends beyond the ears or bifurcated web portions 5 of the casting.

The coupler carrier iron portion or sill tie member 3 of the combined casting is 65 preferably formed with a web 18 and de-

pending flanges 19 at opposite edges thereof. The end portions of said web are substantially horizontal and flat but the intermediate portions 20 thereof are bowed downwardly or depressed, thereby increasing the size of 70 the opening between the striking casting portion, sill tie portion and connecting webs or flanges 16. The depending flanges 19 follow generally the curvature of the web 20, the ends, however, preferably merging 75 with the ends of the web 20 and the corresponding upright flanges or webs 16, as shown particularly in Figure 3. The flat end portions 21 of the web 18 are positioned at the proper elevation for supporting the 80 carrier block 22, which block is preferably straight and formed in cross section as a hollow rectangle having an upper web 23, a lower web 24 and side webs 25.

For properly retaining the carrier block 85 in place, one of the webs 4 is formed with inwardly extending flange portions 26 providing a pocket 27 adapted to receive the corresponding end of the carrier block 22, as shown most clearly in Figure 3. The pocket 27 may correspond in size with the end of the carrier block so that it receives the same with only normal clearance, thereby serving to retain said member in the desired position at all times. It should also be noted that the spacing between the webs or flanges 16, below the flange 26, is greater than that above said flange thereby providing sufficient space for bodily receiving the end of the carrier block 22. In order to provide for insertion of said block, the other web 4 is provided with a corresponding aperture 28, said block 22 being inserted through said aperture 28 until the inserted or forward end engages in the pocket 27. 100 The length of the block 22 is such that, when one end is engaged in the pocket 27, the other end is engaged in the aperture 28 so that it is retained in place by the web 4 above it, the webs 16 to each side of it and the flat portion 21 of the web 18 below it.

In order to prevent undesired withdrawal of the carrier block 22, the edge of the web 4, above the aperture 28, is preferably provided with an outwardly extending web 29 115 joining the webs or flanges 16 and apertured as indicated at 30 for the reception of a retaining pin or bolt 31. The flat portion 21 of the web 20 is provided with a corresponding registering aperture 32 and both of said 120 apertures are so positioned that, when the pin 31 is in place, the block 22 is not only prevented from withdrawal from the aperture 28 but is prevented from disengaging the pocket 27. Any desired means, such as 125 a cotter (not shown), may be inserted through the hole 33 in the pin 31 to prevent undesired removal thereof. If desired, a wear plate 34 may be applied over the top of the block 22, said wear plate being shown 130

of conventional form comprising a web 35 with flanges 36 on either side thereof. Said wear plate may be retained in central position by snugly positioning the same between the shouldered portions 37 provided on the forward or outer webs 16 as will be understood.

Referring now to the embodiment of my invention illustrated in Figures 4 to 7, inclusive, I have shown a combined casting 1^a very similar to the combined casting 1 of the previous embodiment. The bifurcated webs or ears 5^a extend a shorter distance rearwardly than those of the previous embodiment and the sills 6^a are not slotted to the ends as in the first embodiment but extend forwardly into the coupler stem opening between the striking portion 2^a, carrier iron portion 3^a and web portions 4^a and are connected to said web portions by a plurality of rivets 7^a, as shown most clearly in Figure 4. The rearwardly extending ears 5^a are likewise connected to the sills 6^a as well as to the cheek plates 37, said ears, in the present embodiment, being received between the cheek plates and sills and all three connected by rivets 7^a making a total of five rivets in each sill, thereby corresponding with the previous embodiment.

Another difference between the present embodiment and that of the first embodiment resides in the fact that the retaining pin 31^a is substantially horizontally disposed rather than substantially vertically disposed as in the previous embodiment and extends through apertures 32^a in the web or flange portions 16^a of the combined casting 1^a rather than as described in connection with the first embodiment. The lower portion of the pin 31^a may be substantially flush with the web 21^a of the sill tie portion 3^a or may extend slightly below it, as illustrated particularly in Figure 5. A corresponding end of the carrier block 22^a is retained beneath the forwardly extending portion 26^a of the corresponding center sill, the webs 4^a being spaced a greater distance than in the first embodiment and extending substantially parallel with the webs of the center sills rather than being provided with the ogee curve as shown in Figure 2. It will be appreciated that such a curvature is not necessary in the present embodiment because of the horizontal rather than the vertical positioning of the retaining pin. The other end of said carrier block fits into a pocket 27^a formed, not as in the previous embodiment by an integral flange extending inwardly from the web 4, but by the outward extension 28^a on the corresponding center sill 6^a together with the shoulder formed at the junction between the more widely spaced webs 16^a and those positioned above the carrier block 22^a. Except as specifically described in connection with the present em-

bodiment, the same may correspond substantially with that of the first embodiment.

It will be appreciated that by virtue of the aforescribed construction, I have provided a combined striking casting and sill tie member preferably formed as an integral casting normally surrounding the shank of an associated coupler. The opening provided for said coupler and particularly the butt end thereof, is relatively large, so that it may be of the swivel type such, for example, as described and claimed in my Patent No. 1,431,717 of October 10, 1922, the butt of which is substantially larger than the shank. When the carrier block is in place, it will be appreciated that the net opening is very much smaller so that the shank of the coupler is supported at normal elevation and the butt cannot be removed until after removal of the carrier block. By virtue of having the tie member or carrier iron bowed downwardly or depressed beneath the coupler block, an opening of the requisite size is provided without necessitating a block of unusually great height. A block is provided of a strength corresponding to the weight of the coupler and the span of the carrier block between the flat ends of the sill tie portion of the casting. By inserting the block transversely as previously described and having one end retained in a pocket and the other end retained in the aperture provided for insertion and prevented from undesired removal by a simple retaining pin disposed across the opening, a desirable yet simple construction is provided as will be understood.

Having now described my invention, I claim:

1. A combined casting comprising portions serving, respectively, as a striking casting and sill tie member, said sill tie member being bowed downwardly at its intermediate portion and adapted to support a carrier block on its end portions and a removable carrier block seated on the end portions of the sill tie member and spanning the downwardly bowed portion.

2. A combined casting comprising portions serving, respectively, as a striking casting and coupler carrier iron, said carrier iron portion being depressed at its intermediate portion to provide greater clearance for receiving the butt of an associated coupler, the end portions of said carrier iron portion being relatively flat and adapted to support a carrier block, and a removable carrier block seated on the end portions of the coupler carrier iron portion and extending across the depressed portion thereof.

3. A combined casting formed with portions serving, respectively, as a striking casting and coupler carrier iron, said carrier iron portion being adapted to support a carrier block, and a removable carrier block

In testimony whereof I affix my signature.

DONALD S. BARROWS
